UNITED STATES PATENT OFFICE

WILLIAM J. KEENE, OF CHICAGO, ILLINOIS, ASSIGNOR TO CHICAGO SPRING HINGE COMPANY, OF CHICAGO, ILLINOIS, A CORPORATION OF ILLINOIS

SPRING PIVOT HINGE

Application filed January 10, 1929. Serial No. 331,495.

This invention relates to spring hinges and more especially to a sagless spring pivot hinge for hanging gates or dwarf doors, particularly of the double-acting type.

5 An important object of the invention is to provide a spring hinge of the character specified, more particularly a double-acting spring hinge of novel construction wherein the spring serves to oppose movement of the hinge and door in either direction from a predetermined or central position and in which means is provided for easily adjusting the tension of the spring after the gate has been hung to facilitate properly adapting the hinge to the surrounding conditions.

10 A further object of the invention is to provide an adjusting means which is comparatively indiscernible.

Another object of the invention is to provide an adjustable pintle with a locking device which permits the setting of the door to remain at rest in any desired position intermediate or at either side, in addition to providing a double-acting spring hinge in which the mechanism is housed so that all of the operating parts are enclosed and held against displacement.

15 Another object of the invention is to provide a bearing bracket for the pintle in the nature of a ball and socket joint which will automatically center itself or may be easily adjusted to align the pivots of the gate or door to cause the latter to hang plumb and prevent binding and friction between the parts by reason of being off center and positively clamped or held in adjusted position so that it will not shift but will remain in alignment, especially should the bottom edge of the door and thus the top of the hinge not be perpendicular to the attaching side of the bracket or the pintle perpendicular to the bearing portion of the bracket, thereby eliminating binding and excessive friction between the parts in use.

20 Other objects and advantages will be apparent as the description proceeds.

In the accompanying drawings:

Fig. 1 is a front elevation showing a gate or door hung by the novel hinge constituting the subject matter of the present invention,

Fig. 2 is an enlarged end elevation looking toward the free end of the gate.

Fig. 3 is a sectional plan view taken on the section line 3—3 of Figure 4.

Fig. 4 is a sectional view taken on the line 55 4—4 of Figure 3.

Fig. 5 is a vertical section taken on the line 5—5 of Figure 4.

Figs. 6, 7, 8 and 9 are sectional views taken on the section lines 6—6, 7—7, 8—8 and 9—9 60 of Figure 4.

Fig. 10 is an elevation of the hinge pintle or stem.

Fig. 11 is an enlarged fragmentary sectional view showing the bracket for supporting the hinge pintle and aligning the pivots of the gate.

Fig. 12 is a sectional view taken on the section line 12—12 of Figure 11, and

Fig. 13 is a plan view of a knurled washer 70 employed with the pintle, supporting an adjusting bracket.

Referring to the drawings in detail, 13 indicates a partition such as used in offices or compartments. 14 designates a gate or dwarf door adapted to be pivoted thereto by means of my novel hinge structures which are indicated as a whole at 15 and 16 respectively. The latter structure comprises a double-acting spring hinge which maintains the gate 14 80 in a predetermined position and permits it to swing either way. This hinge structure comprises a barrel or cylinder 17 in the form of an inverted cup-shaped casing which fits against and is secured to the lower edge of 85 the gate or door 14 as by means of screws 18 extending through apertures in an extension 19 extending laterally from the casing 17 at the top. The casing and extension are flat on the top except for an axial extension 20 in the form of a bearing sleeve closed at the top and projecting from the top of the casing 17, which latter is circular in horizontal section. The extension 20 is received in a counterbore 90 drilled in the lower edge of the door and serves to anchor the casing against shifting at this point. It also forms a seat for the upper end of a stem or pintle 21 and is preferably formed with an annular ball race for ball bearings 22 against which the beveled 95

100

upper end 23 of the pintle engages for supporting the weight of the gate and permitting the latter to turn with ease. The pintle or stem extends centrally down through the casing 17 and projects from the lower end thereof.

It will be noted that the upper portion of the pintle is enlarged with respect to the reduced portion 24 immediately therebeneath, which portion is formed with a substantially radially extending abutment lug 25 near its upper end. Below the reduced portion 24, the normal diameter of the pintle results in a shoulder 26 and another reduced portion 27 is formed therebeneath, having a peripheral groove 28 extending around approximately a little more than one-half the circumference thereof. The lower end is still further reduced as indicated at 29 and threaded. This reduced portion results in a downwardly facing shoulder 30 at the lower end of the portion 27, which is larger in diameter than the portion 29. The shoulder 30 is made plain or smooth but becomes notched or knurled by the knurling or teeth of a washer 43 biting into the shoulder as indicated at 31, particularly as seen in Figure 11 of the drawings.

At one side of the casing 17 is an internal vertically extending rib 32 and at the opposite side an enlargement or external rib 33, each of which has a threaded aperture at the lower end for receiving screws 34, whereby a bottom plate 35 may be secured over the lower open end of the casing 17 for enclosing and holding assembled, the mechanism of the spring hinge. It is, of course, to be understood that the bottom plate 35 has suitable openings through which the screws 34 extend. This plate also has a central and relatively enlarged circular opening 36 preferably reinforced by a depending flange 37 extending around the opening to afford a bearing for a sleeve 54 formed on a collar 51. The lower end of the pintle or stem 21 extends through the sleeve 54 and projects down considerably therefrom.

The flange 37 is provided with a cut-away portion or recess 38, or the flange 37 may be considered as a projection on the bottom plate for a purpose to be hereinafter made more fully apparent. The projecting end of the pintle extends through a circular opening 39 in the upper horizontal portion of a bracket 40, the bracket being of angular formation and provided with a depending part or side flange 41, or otherwise constructed so as to be secured to the post, partition, or railing 13, or any other support to which the gate 60 is desired to be attached, as by means of screws 42.

The pintle is held against turning movement in the bracket 40 but is adapted to be angularly adjusted at this end for aligning the lower pivot formed by the pintle with the

upper pivot of the gate, as will be later described, in order that there will be no binding on the pivots and so that the gate may be properly adjusted to hang true or plumb and also by turning the pintle axially, properly adjusted with respect to the jamb or edge of a co-acting door. A washer 43 is mounted on the pintle 21 against the plain shoulder 30, as at 31, and the upper face of the washer is knurled, as indicated at 44 to bite into the shoulder 30. The bottom face of the washer 43 is also knurled and rounded in convex formation, as indicated at 45, to seat in a corresponding concavity or recess 46 in the top of the bracket arm 40 around and concentric to the opening 39 therethrough, the face of recess 46 being rough.

It should be noted that the lower portion of the pintle, which is threaded, fits loosely in the opening 39 so that it may be adjusted laterally or angularly in a vertical arc, and universally in an arc of 360 degrees horizontally, so as to secure proper alignment of the pivots, that is, the lower pivot formed by the pintle and the upper pivot of the gate, to be mentioned hereinafter. The bottom face of the bracket arm 40 is also made convex, as indicated at 47, concentric to the faces 45 and 46 so as to cause the pintle to automatically center itself in the bracket to prevent binding. A nut 48 is threaded on the pintle end 29 and its top face is concave as at 49 to fit the convexity 47 in any position of adjustment of the pintle angularly in the opening 39. Then by tightening the nut, the co-acting faces will be forced together and by reason of the knurled surfaces 44 and 45 gripping the downwardly facing plain shoulder 30 of the pintle and the rough surface 46, respectively, together with the friction between the parts caused by the binding engagement and conformity of the concaved face 49 of the nut 48 with the convex surface 47 of the bracket 40, the parts will be positively held against relative rotation and lateral displacement when once adjusted and will not slip out of alignment as it would if the top face of the nut were flat.

By the construction just described, the pintle 21 is held against turning movement. At the upper and lower ends respectively of the pintle 21 within the casing 17 are collars 50 and 51 which loosely engage the pintle. The upper collar 50 is mounted upon the enlargement at the upper end of the pintle above the abutment lug 25. This collar is provided with a segmental flange 52 terminating in a shoulder 53 adapted to engage the abutment 25 in a clockwise direction, as seen in Figures 5 and 7, the latter figure being a section looking upwardly. The lower collar 51 is mounted on the reduced portion 27 of the pintle 21 and has a depending sleeve portion 54 extending down through the enlarged opening 36 in the bottom plate 35 in which it

has a bearing. Near its lower end the sleeve portion 54 is provided with a series of radial holes 55 adapted to receive a pin 56 which is exposed in the recess or cut-away portion 38 of the flange 37 and has an enlargement or flange 57 adapted to limit its inward displacement into the groove 28. This structure affords an adjustable stop or limiting means in connection with the lower collar 51 corresponding to the fixed stop for the upper collar 50 provided by the shoulder 53 of the segmental flange 52 and serves as a means for regulating, i. e., increasing or decreasing the tension of a spring 58 which extends between the collars 50 and 51 and telescopes on the lower and upper extremities respectively of these collars against their annular flanges 59 and 60 respectively. The ends of the spring are bent inwardly as shown at 61 to engage 20 in vertical grooves 62 of the flanges 59 and 60 respectively so that the tension of the spring serves to hold the shoulder 53 against the abutment 25 and a projection 63 against the rib 32, while the pin 56 is held against one shoulder of the flange 37 produced by the 25 cut-out 38.

The shoulder or projection 63 engaging the rib 32 serves for the purpose of connecting the spring to the casing 17, so that the operation of the gate or door is under the control of the spring. The projection 63 normally engages one side of the rib 32 and the pin 56 normally engages one end of the flange 37 so that the gate may be swung in an angle of 35 about 180 degrees. Assuming that the gate is swung in the direction of the arrow X in Figure 7, the rib 32 will rotate with the casing 17 in a clockwise direction, moving the projection 63 and the collar 50 with it so that 40 the shoulder 53 will be withdrawn from the stationary stop or abutment 25 on the stem or pintle 21. Inasmuch as the lower end of the spring 58 is connected to the collar 51 and the upper end of the spring is connected to the 45 collar 50, which has the shoulder 53 engaged with the stop or abutment 25 of the pintle 21, the collar 51 and the lower end of the spring will be held by the pin 56 against turning movement, with the result that the swinging 50 of the gate in the direction of the arrow X puts the spring 58 under sufficient tension so that when the gate is released, it is returned by the spring to the normal position. On the other hand, when the gate is swung in 55 the direction indicated by the arrow Y in Figure 7, a reverse action of the spring mechanism takes place—that is, the projection 63 will tend to move away from the rib 32 but this is prevented by engagement of the shoulder 53 with the stationary abutment 25, causing the collar 50 to remain stationary 60 while the spring is pressed under tension. Previously, the pin 56 is engaged with one end of the groove or recess 28 in the pintle 21 and as the lower collar 51 is thus rotated, the

pin 56 will move way from its shouller, thereby creating a tension of the spring which serves to return the gate or door to the normal position in the opposite direction, when released. In both instances, the gate will be 70 returned to a neutral position automatically by the spring 58 regardless of the direction in which the gate is swung. However, the tension of the spring may be easily adjusted after the gate has been hung by simply inserting a pin in one of the openings 55 and turning the collar 51. After withdrawing the pin 56, then reinserting it in another opening 55 according to the tension desired by turning in one direction, the tension may 80 be increased, and by turning in the opposite direction, the tension will be lessened or may be released entirely. This is a very desirable feature to adapt the hinge to conditions, depending upon the tension desired or the 85 weight of the gate or door.

The companion hinge structure 15 which is employed in connection with the hinge structure 16 for pivotally mounting the door or gate 14, may be of any desired type. 90 However, I prefer to employ the construction shown in Figures 3 and 4 which comprises a plate 64 which is mortised into the upper end of the gate and is secured by screws 65 passing through suitable apertures in the plate. 95 This plate has a socket 66 forming a bearing for a pin or stud 67 on the underside of the angular bracket arm 68. The arm has a horizontal portion which is provided with a pin and a vertical or flange portion 69 which may 100 be secured to the post or partition structure 13 in any suitable manner, as by means of screws 70.

An anti-friction or ball bearing 71 is preferably recessed into the top of the plate 64 105 around the socket 66 and has a pair of raceways or cups receiving the balls therebetween, the inner cup being frictionally held on the pin 67 so that the gate may freely turn at this point without undue friction and wear on the parts. In conjunction with this top bearing or pivot, the adjustment of the lower end of the pintle 21 angularly in a horizontal direction or arc substantially concentric to the top of the pintle and the top pivot 110 of the door, will permit proper alignment of the pivots so that the door may be properly fitted and will swing true, even though the bottom edge of the door is not normal to the partition 13.

The adjustment of the pintle and spring together with the locking device can be readily accomplished without dismantling any of the parts and permits setting of the door to remain at rest in any desired position.

While I have shown and described my invention in a preferred form, I am aware that various modifications and changes may be made therein without departing from the 120

principles of the invention, the scope of which may be determined by reference to the appended claims.

I claim as my invention:

- 5 1. In a spring pivot hinge, a bracket adapted to be secured to a support, a casing adapted to be secured to a swinging element having a bearing at the top, a pintle pivoted in the bearing and having its lower end engaged in the bracket with means for lateral adjustment and held against turning movement, an abutment on the pintle, the casing having an internal rib, collars loosely engaged on the upper and lower portions of the pintle and each provided with a flange having a groove, one collar flange having a shoulder adapted to engage the abutment, said collar also having a lateral projection adapted to engage the rib, a coil spring extending between the collars and having its ends bent inwardly to engage the grooves to hold the shoulder against the abutment and the projection against the rib, a bottom plate on the casing having a depending circular flange with a cut-away portion and a central circular opening much larger than the pintle, the lower collar being formed with a sleeve bearing in the flange around the pintle and having a series of radial holes, the pintle having a peripheral recess in line with the holes producing end shoulders, and a pin disposed in the cut-away portion for engagement with one of said holes and the recess, said pin normally engaging a shoulder in one end of the cut-away portion of the flange and at one end of the recess and adapted to be interchangeably engaged in another of said holes for adjusting the tension of the spring.
- 10 2. In a spring pivot hinge, a casing, a stationary pintle, a spring in the casing, means co-acting between the spring, pintle and casing to cause winding of the spring upon actuation of a door or other swinging element to which the casing is attached, said means including collars mounted on the pintle and to which the ends of the spring are connected, one collar having a sleeve extending through the casing around the pintle, the casing being formed with stops, and a pin displaceably engageable in an opening in the sleeve and adapted to engage one of said stops whereby the tension of the spring may be adjusted exteriorly of the casing by turning the sleeve and its collar with the pin removed and then reinserting the pin.
- 15 3. In a spring hinge of the class described, the combination of a pair of hinge members, a pintle secured to one of said members and engaging the other for pivotally connecting the same, spaced collars rotatably mounted on said pintle between said hinge parts, a torsion spring surrounding said pintle, extending between said collars and connected at its opposite ends to said collars, means for connecting one of said collars to said pintle

and to one of said hinge members for permitting rotation of the collar around the pintle in one direction only, and adjustable means for similarly connecting the other collar to the pintle including a pin adjustably mounted in and extending through said collar, said pintle having a recess extending only partially around the circumference thereof for receiving the inner end of said pin, and said hinge member having a shoulder adapted to be engaged by the outer end of the pin.
